UNITED STATES PATENT OFFICE.

JOHN QUINCY REED, OF NEW YORK, N. Y., ASSIGNOR TO THE BUTTERICK PUBLISHING COMPANY, (LIMITED,) OF SAME PLACE.

DESIGN FOR A LADY'S BASQUE.

SPECIFICATION forming part of Design No. 14,511, dated December 25, 1883.

Application filed October 27, 1883. Term of patent 3½ years.

To all whom it may concern:

Be it known that I, JOHN QUINCY REED, of the city, county, and State of New York, have invented and produced a new and original Design for a Pattern of a Lady's Basque with Puff, (numbered 8,950;) and I do hereby declare that the engraved prints accompanying this specification convey to any one accustomed to using paper patterns a clear understanding of how a garment made up by the pattern will appear.

The design shows closely-fitted fronts, having buttons all the way down, with a shirred drooping puff on their upper part, a close-fit-

ted back that displays plaits at the lower end 15 of its center and side seams, a rolling collar, and coat-sleeves. It is of uniform depth at the front and sides, and is much deeper at the back than in front.

What I claim as my invention, and desire to 20 secure by Letters Patent, is—

The design for a lady's basque with Pompadour puff, as shown in the engraved prints accompanying this specification.

JOHN QUINCY REED.
